UNITED STATES PATENT OFFICE.

CARL H. ERICSON, OF BOSTON, MASSACHUSETTS.

MANGLE.

SPECIFICATION forming part of Letters Patent No. 622,338, dated April 4, 1899.

Application filed January 18, 1898. Serial No. 667,070. (No model.)

To all whom it may concern:

Be it known that I, CARL H. ERICSON, of Boston, (Roxbury,) in the county of Suffolk and State of Massachusetts, have invented

5 certain new and useful Improvements in Mangles, of which the following is a specification.

This invention has relation to mangles, and has for its object to provide certain improvements in the same whereby fabrics may be 10 ironed more efficiently than heretofore and whereby a superior gloss and finish may be imparted thereto.

The more specific object of the invention is to provide the mangle with certain improvements whereby the cloth or fabric to be ironed 15 is thoroughly dried or desiccated as it is being ironed and polished and is not allowed to leave the mangle in a damp condition.

To these ends the invention consists of a 20 mangle provided with certain features of construction and arrangements of parts, all as illustrated upon the accompanying drawings and now to be described in detail, and finally pointed out with particularity in the claims.

25 Referring to the drawings, Figure 1 represents in side elevation a machine embodying my invention. Fig. 2 represents a longitudinal vertical section through the same, the frame not being shown. Fig. 3 represents a 30 longitudinal section through the cylinder and the iron. Fig. 4 represents a longitudinal section of a device for desiccating the fabric. Fig. 5 represents the yielding adjusting devices for the cylinder.

35 Referring to the drawings, *a* indicates the side standards of the frame in which the operative parts are mounted. This frame may be of any shape desired and is provided with journal-bearings for the shafts which impart 40 motion to the cylinder. The main driving-shaft *b* is mounted in bearings *a* *a'* on the frame and is provided with belt-pulleys *b'* *b''*, one of which is fast upon the shaft and the other of which is loose. The shaft is further

45 provided with a worm *b'*, intermeshing with and driving a gear-wheel *c* on the shaft *c'*, upon which is secured a pinion *c''*. This pinion *c''* intermeshes with and drives a gear-wheel *d*, connected with a cylinder *e*. The 50 periphery *e'* of the cylinder is provided with inwardly-projecting annular flanges *e''*, to which are secured the ends of the cylinder, said ends consisting of disks *e'''*, formed on or

secured to hollow stud-shafts *e⁴* *e⁵*. The gear-wheel *d* is secured upon the stud-shaft *e⁴*, so 55 that when the shaft *b* is rotated the cylinder is slowly rotated.

The stud-shafts *e⁴* *e⁵* are journaled in blocks *f*, sliding in ways or guides *a²* *a^{2'}* on the frame, as shown in Fig. 1, and the said blocks are 60 secured to and rest upon the ends of supporting-bars *f'*, sliding through boxes *a³*, as shown in Fig. 1.

In each box *a³* is placed a spring *f⁹*, and the supporting-bar *f'* is divided into two portions, each provided with a disk *f¹⁰*, between which is arranged the spring, so that the cylinder is supported yieldingly to permit the 65 passage of fabrics between it and the iron, as I shall subsequently describe. 70

Upon the ends of the bars *f'* are placed rollers *f²* resting upon cams *f³*, secured upon a shaft *f⁴*. Likewise secured to the shaft *f⁴* is a rack-segment *f⁵*, with which a worm *f⁶* intermeshes, the said worm being upon the 75 end of a shaft *f⁷*, mounted in a bearing *a⁴* and provided on its end with a hand-wheel *f⁸*. By turning the hand-wheel *f⁸* the shaft *f⁴* may be partially rotated to raise or lower the cylinder *e*, the path or plane of movement of 80 the axis of the said cylinder being substantially tangential to the pinion *c''*, so that the pinion *c''* and gear *d* will not become disengaged.

About the periphery of the cylindrical roll 85 *e* is placed a thick layer *e⁶* of felt or equivalent material, and the said periphery *e'* is provided with numerous perforations *e⁷* for a purpose to be described.

Secured to supports afforded by the frame 90 *a* is an iron *g*, having a smooth concave inner face *g'*, concentric with the periphery of the cylinder. The iron is concavo-convex in form and is hollow, being provided with a steam-inlet *g²* and a steam-outlet *g³*, whereby it may 95 be heated to the desired temperature.

In front of the cylinder and the iron is a drier or desiccating device which is in shape substantially the half of a cylinder—that is to say, it has a flat top plate *h* and a curved 100 under plate *h'* and semicircular end walls *h''*. The convex under plate *h'* is provided with a smooth outer surface, which surface, together with the concave surface of the iron, forms substantially an ogee or compound curve. 105 The plate *h'* of the desiccating device is pro-

vided with numerous perforations, similar to those in the periphery of the cylinder or drum *e*.

Passed under the convex surface of the desiccating device and over the drum between it and the iron is an endless band or belt *i*, supported by pulleys or rolls *i'*, *i''*, and *i'''*, as shown in Figs. 1 and 2. The roll *i'* is located near the top of the desiccating device, so that the belt or band comes in contact with the under face of the plate *h'*, and the pulley *i'''* is located in position to carry the belt away from the drum as soon as it passes from under the iron *g*.

15 The pulleys are all mounted on shafts journaled in bearings on the frame, and in order to adjust the tension of the belt the bearing-blocks *i''* for the roll or pulley *i'''* are arranged to slide in guides *i''* and are each internally threaded to receive a screw-bar *i''*. The screw-bars are provided with bevel-gears *i''*, intermeshing with and driven by similar gears *i''* on a transverse shaft *i''*. A hand-wheel *i''* is secured upon the shaft to turn it and cause 20 the bars *i''* to slide the blocks *i''* in their guides.

25 Placed within the cylinder or drum are two headers *j j'*, both having hubs *j' j''*, supported upon the inwardly-projecting ends of the tubular shafts *e' e''* and connected by longitudinally-arranged pipes *j''*.

30 Steam is introduced into one of the headers through the pipe *k'* and passes therefrom through the duct *k'* into the opposite header and back through the pipes *j'' j''* to the exhaust-outlet *h*, passing through the tubular shaft *e'*. Through the tubular shaft *e'* is introduced a steady stream of air by means of a fan or blower *n*, connected thereto by a duct *n'*.

35 40 In the desiccating device are two headers *l l'*, connected by longitudinally-arranged pipes *l''*, and steam is introduced into the header *l* through a steam-inlet pipe *l''* and out from the header *l'* by an exhaust-pipe *l''*. The

45 stream of air is likewise introduced into the desiccating device through the pipe *n''*, connected to the fan or blower *n*.

The fabric to be dried and ironed is presented to the action of the belt *i* and is carried thereby under the convex plate *h'* of the desiccating device and between the cylinder or drum and the iron, and by the time it is carried out from the latter it is thoroughly dried and is glossed or polished with a superior finish.

50 55 The fabric being wet is first carried by the desiccating device, and the air which is forced thereinto is heated by the steam-pipes and passes out through the minute perforations, drying the fabric sufficiently to enable it to be properly ironed and polished when it reaches the next device. The remainder of the moisture from the fabric is taken up by the felt upon the drum, so that the fabric is discharged in a dried condition.

60 65 It will be observed that a large portion or a little more than half of the entire periphery of the drum is exposed, so that the heated

air is forced out through the minute perforations and the felt is thoroughly dried before it again engages the other portion of the fabric. 70

Owing to the fact that the cylinder is vertically supported on springs, so that the weight of said cylinder is yieldingly supported, it is feasible to obtain almost any amount of pressure on the goods less than 75 the weight of the cylinder. Thus when it is desired to subject some articles to light pressure the cylinder can be adjusted so that there is but a light spring-pressure against or toward the iron. 80

Having thus explained the nature of the invention and described a way of constructing and using the same, though without attempting to set forth all of the forms in which it may be made or all of the modes of its use, 85 I declare that what I claim is—

1. A mangle comprising an iron, a cylinder covered with a suitable elastic material, and having its periphery formed with numerous perforations, mechanism for forcing a stream 90 of air into the cylinder, mechanism in the cylinder for heating the air, and a belt for feeding the fabric to be ironed.

2. A mangle comprising an iron, a cylinder covered with elastic material and coacting 95 with said iron and having a considerable portion of its periphery exposed, said cylinder having numerous perforations in its periphery, a belt for feeding the fabric in contact with the iron, mechanism for forcing a stream 100 of air into the cylinder, and mechanism for heating the air.

3. A mangle comprising an iron, a cylinder coacting with the iron and having its periphery perforated, a desiccating device having 105 its operative surface perforated, a belt or band in contact with both the cylinder and the desiccating device, and mechanism for forcing air through the perforations in the cylinder and drier. 110

4. A mangle comprising an iron, a cylinder coacting with the iron and having its periphery perforated, a desiccating device having its operative surface perforated, a belt or band in contact with both the cylinder and 115 the desiccating device, mechanism for forcing air through the perforations in the cylinder and drier, and mechanism in the cylinder for heating the air.

5. A mangle comprising a concavo-convex 120 iron, a cylinder coacting therewith and having its periphery perforated, a drier having a convex perforated surface, a band or belt passing between the iron and the cylinder and under the convex surface of the drier, 125 and mechanism for forcing heated air through the cylinder and drier.

In testimony whereof I affix my signature in presence of two witnesses.

CARL H. ERICSON.
